Patented Jan. 1, 1963

194,333

COMBINED BOX AND PIN CUSHION

Romaine C. Chapman, Cheshire, Conn., assignor to Scovill Manufacturing Company, Waterbury, Conn., a corporation of Connecticut

Filed Sept. 21, 1961, Ser. No. 66,798

Term of patent 7 years

(Cl. D58—12)

Fig. 1

Fig. 2

Fig. 4

Fig. 3

Fig. 5

FIG. 1 is a perspective view of a combined box and pin cushion embodying my new design;

FIG. 2 is a top plan view of the same;

FIG. 3 is a side elevation of the same;

FIG. 4 is a rear elevation of the same; and

FIG. 5 is a front elevation of the same.

I claim:

The ornamental design for a combined box and pin cushion, substantially as shown.
